UNITED STATES PATENT OFFICE

146,976

DESIGN FOR A KEY HOLDER

Oliver R. Lesley, Clayton, Mo.

Application April 30, 1946, Serial No. 129,134

Term of patent 7 years

(Cl. D17—14)

To all whom it may concern:

Be it known that I, Oliver R. Lesley, a citizen of the United States, residing at Clayton, in the county of St. Louis and State of Missouri, have invented a certain new, original, and ornamental Design for Key Holders, of which the following is a specification, reference being had to the accompanying drawing, forming part thereof.

Fig. 1 is a perspective view of a key holder, the same being shown in open position.

Fig. 2 is a perspective view of the key holder shown in closed position.

Fig. 3 is a perspective view of the key holder in closed position and shown as looking from the end opposite that shown in Fig. 2.

Fig. 4 is a top plan view of the key holder.

Fig. 5 is an end view of the key holder.

Fig. 6 is a side elevation of the key holder.

Fig. 7 is an end view of the key holder showing the end opposite that shown in Fig. 5.

I claim:

The ornamental design for a key holder, as shown and described.

OLIVER R. LESLEY.
